UNITED STATES PATENT OFFICE.

JAMES M. ROBERTS, OF RICES LANDING, PENNSYLVANIA.

SHARPENER.

1,335,603.

Specification of Letters Patent. Patented Mar. 30, 1920.

Application filed May 10, 1919. Serial No. 296,102.

To all whom it may concern:

Be it known that I, JAMES M. ROBERTS, a citizen of the United States, residing at Rices Landing, in the county of Greene and 5 State of Pennsylvania, have invented certain new and useful Improvements in Sharpeners, of which the following is a specification.

My invention relates to new and useful 10 improvements in sharpeners.

The object of my invention is to provide a sharpener for knives, scissors, and the like, in which both sides of the cutting edge thereof may be sharpened, and also providing 15 means whereby either side of the cutting edge may be sharpened at different angles.

Another object of the invention is to provide a sharpener of this character, in which the sharpening cylinders are composed of 20 a series of rotatably supported disks spaced apart, so that the disk of one cylinder overlaps the disk of the other, so that a greater sharpening surface is obtained.

A still further object of the invention is 25 to provide a cheap, simple and effective structure, whereby the heretofore mentioned objects may be carried out, as hereinafter more fully set forth.

In the accompanying drawings:

30 Figure 1 is a perspective view of my improved sharpener;

Fig. 2 is a longitudinal vertical sectional view; and

Fig. 3 is a horizontal sectional view taken 35 on the line 3--3 of Fig. 2.

Referring now to the drawings, 1 represents the base of my improved sharpener, which, as shown, is of rectangular form and carries on its upper face the upwardly extending housing 2, which is integral with the base. The base is provided with openings 3, whereby the same may be screwed upon a table, or other support 5, by means of screws 4, as shown in Fig. 2 of the drawings.

40 The housing 2 is of a rectangular form; slightly smaller than the base 1, and has its side walls provided with upwardly curved portions 6 and 7, having openings 8 and 9, in which are two bolts 10 and 11 which 45 extend across the housing, and upon which are mounted the sharpening cylinders, as will now be described.

The sharpening cylinders are formed of 50 a series of disks 12, and, as shown, are comparatively thin with straight outer edges 13 and provided with openings 14 to receive

the bolts 10 and 11. Any number of cutting disks may be used, and between each disk is a washer 14, the diameter of which is considerably less than that of the sharpening 60 disk. The washers, like the disks, are provided with openings through which the bolts pass and there are sufficient disks and washers on each bolt to nearly fill the space between the sides of the housing 2, so that 65 there is a slight longitudinal movement of the cutting disks on the bolts. The bolts are so positioned in the housing and the washers and cutting disks on one bolt are so positioned that they pass between the 70 sharpening disk carried by the other bolt, as clearly shown in Figs. 2 and 3 of the drawings.

In the ordinary sharpening of a knife, and when it is desired to sharpen both sides, 75 it is placed between the two sets of sharpening disks and drawn transversely of the housing, so that the sharp edges of the disk engage both sides of the knife and sharpen the same.

The housing 2 has its ends 15 and 16 extending upwardly a considerable distance to form the guides for sharpening one side of the cutting edge of a knife, scissors, or other implements. The end 15, as shown, is 80 thickened or drawn inwardly, as indicated at 17, above the sharpening cylinder, so that a knife or scissors blade placed against the inner face thereof, and drawn transversely of the housing will be sharpened. The end 16 is thickened, or drawn inwardly, as indicated at 18, to a greater extent than the end 17 so that its inner face is closer to the top of the disk, and whereby the point of contact of the knife is at a less angle when 90 held against the end 16 than when held against the end 15.

By this arrangement, applicant has produced a sharpener in which the proper bevel can be given to the cutting edges of different 100 implements on either side, by drawing the tool across the same from different sides.

While I have shown the base, housing and guides made integral of metal, it will be understood that the same could be made of 105 any material and built up of sections, in any desired manner.

Having thus described my invention, what I claim as new and desire to secure by Letters Patent, is:

110 1. A sharpener comprising a support, a pair of circular overlapping sharpening

members rotatably supported therein, and vertical guides carried by the ends of the support at points outward from the axes of the sharpening members whereby both edges 5 or either edge of the tool can be sharpened by a single operation.

2. A sharpener comprising a support, a pair of circular cylindrical sharpening members rotatably supported therein and 10 formed of spaced overlapping disks and vertically upwardly extending guides carried by the ends of the support at points outward from the axes of the sharpening members whereby both edges or either edge of the tool 15 can be sharpened by a single operation.

3. A sharpener comprising a rectangular housing, a pair of parallel cylindrical sharpening members rotatably supported therein, upwardly extending guides carried by the 20 ends of the housing and extending upwardly

beyond the periphery of the cylindrical sharpening members, whereby either edge of the instrument may be sharpened.

4. A sharpener comprising a support, a pair of parallel cylindrical sharpening members 25 therein, upwardly extending guides carried by the ends of the support and drawn inwardly over the cylindrical sharpening members, one guide extending a greater distance over the sharpening member than the other guide, whereby different bevels will be given implements held against the two guides.

In testimony whereof I affix my signature in the presence of two witnesses.

JAMES M. ROBERTS.
